CLAIM

The ornamental design for a muffler clamp, substantially as shown.

DESCRIPTION

FIG. 1 is a perspective view of a muffler clamp showing my new design;

FIG. 2 is a side elevational view thereof, the opposite side being a mirror image of the side shown;

FIG. 3 is an end elevational view thereof with a portion of the U-bolt cut away the opposite end being a mirror image of the end shown;

FIG. 4 is a top plan view thereof;

FIG. 5 is a bottom plan view thereof; and

FIG. 6 is a sectional view taken in the direction of the arrows on line 6—6 of FIG. 2.

FIG.1

FIG.6
